GARMENT CONSTRUCTION

Pansy H. Jackson, Chicago, Ill.

Application August 8, 1934, Serial No. 738,904

1 Claim. (Cl. 2—73)

The present invention relates to garment constructions, and has particular reference to an improved construction for securing of garments to the wearer.

5 Many garments for feminine wearers are supported by means of shoulder straps passing from the front of the garment over the wearer's shoulders and being secured to the back portion of the garment. This type of supporting structure is 10 widely used for garments such as brassières and under dresses or slips. Commonly, each garment is provided with shoulder straps, and as it is customary to wear both brassières and slips, particularly where summer outer dresses are worn, the 15 wearer is somewhat burdened with an unduly large number of shoulder straps which may break or slip off the shoulder with embarrassing results.

A principal object of the present invention is the provision of an improved type of under garment having shoulder straps and supporting means for properly positioning an additional under garment about the body of the wearer without the necessity of shoulder straps.

20 A further object is to provide a combined brassière and under dress of the slip type in which the slip is supported without additional shoulder straps.

25 A still further object of the invention is to provide a novel supporting means by which one garment may be releasably attached to another garment and supported upon the body of the wearer without the necessity for providing separate shoulder straps or other similar securing means.

30 These and other objects will be apparent upon a consideration of the following illustrative and explanatory description of a preferred embodiment of my invention, and by reference to the accompanying drawing in which:

35 Fig. 1 is a perspective view of a combined brassière and slip structure in accordance with my invention;

40 Fig. 2 is a perspective view of the brassière shown in Fig. 1;

45 Fig. 3 is a perspective view of the slip shown in Fig. 1;

50 Fig. 4 is a view similar to Fig. 3 and showing separate shoulder straps attached to the slip;

55 Fig. 5 is an enlarged detail view of the attaching mechanism by which the slip shown in Fig. 3 is attached to the brassière shown in Fig. 2, the attaching mechanism being shown in closed or locked position; and

Fig. 6 is a view of the locking mechanism shown in Fig. 5 in which the complementary locking elements are then released.

The usual type of brassière consists of a body portion which is fitted somewhat snugly about the body of the wearer and secured at its rear or side by means of hook and eye elements or similar fastening devices of the well known type. 5 To prevent the brassière from working downwardly about the body of the wearer, it is customary to provide shoulder straps which are attached at the rear of the brassière and extend over the shoulders to the front or breast-supporting portions of the brassière. Due to the close fit of this garment there is little likelihood of the shoulder straps being displaced from the shoulders of the wearer. Also, it is customary in 10 feminine apparel to wear a somewhat loosely fitting slip or under dress, one of the principal functions of which is to prevent light from passing through the outer dress of the wearer. The slips also cover the brassière and are provided with shoulder straps positioned somewhat in the 15 same manner as the shoulder straps of the brassière. Thus, when both brassière and slip are worn, the shoulders of the wearer must carry a 20 plurality of straps which commonly may be seen about the collar of the outer dress and are suggestive of the under garments. Also, the slip 25 straps tend to fall from the shoulders of the wearer. In accordance with my invention I have found that by providing a suitable combination between the slip and brassière, the shoulder 30 straps of the former may be eliminated and a neat and secure attachment of the slip obtained. As shown in Fig. 2 of the drawing, a brassière A 35 of usual construction and having a body band 10 with its rear ends attached at 11 by any suitable arrangement such as hooks, is provided with shoulder straps 12. The shoulder straps have their rear ends secured to the brassière at its rear portion, and the front ends of the straps are secured to the upwardly extending points of 40 breast portions 13 of the brassière. Adjacent the points of attachment of the straps 12 to the rear of the brassière A and to the breast portions 13 of the brassière are provided additional securing devices indicated generally by the numeral 14. 45 Preferably the straps 12 are permanently attached to the brassière as by sewing and the additional securing means 14 may be permanently attached to portions of the shoulder straps above or below the points of attachment of the shoulder straps to the brassière.

50 In Fig. 6 is shown a particular attaching means which I have found to be satisfactory in securing an under dress to a brassière in accordance with my invention. The figure shows in 55

detail the structure for securing the slip to the breast portion of the brassière, and it will be understood that the same mechanism may be employed for securing the rear portion of the slip to the rear portion of the brassière, as to the rear ends of straps 12. To the strap 12 at a point preferably above its attachment to the brassière is secured the female member 15 of a snap fastening device. Secured to the strap 12 at a point slightly below the member 15 is the eye 16 of a hook and eye fastening device.

The slip B which is to be secured to the brassière has a body portion 17 which terminates at the upper front portion of the garment in breast receiving portions 18 of a shape somewhat similar to the corresponding portion 13 of the brassière. Preferably the elements 18 of the slip are of such size as to cover the brassière, and at their upper corners the elements 18 are provided with bands or ribbons 19 which may be of similar texture and color as the bands 12 on the brassière. These ribbons 19 are attached to the under side of the slip and at the upper portion of the ribbons is provided a male member 20 of the snap fastening device. Just below the snap element 20 is provided a hook element 21 of the hook and eye fastening device, this hook being positioned so as to be operable to engage the eye member 16 described heretofore when the male element 20 of the snap fastening device is in engagement with the female member 15 thereof.

As before stated, the combined snap and hook and eye fastening devices preferably are provided adjacent each of the points of attachment of straps 12 to the brassière A, it being understood that these devices are secured from the outside of the brassière. To secure the slip to the body of the wearer, the brassière is placed about the body in the usual manner and the slip then placed about the body in the usual manner. The fastening means between the slip and brassière are engaged by first interlocking the hook element 21 with the eye element 14. When this hook is in engagement in the position shown in Fig. 5, the male member 20 of the snap device is in position to be engaged with the element 15 on the brassière to complete the interlock. The snap fastening device may be classed as a tight-fitting fastening device, while the hook and eye structure may be classed as a loose or easily displaced securing device. I have found that the combination of these two types of securing mechanisms is particularly effective for the purpose described. It will be noted that the snap fastening device is so positioned as to make the accidental release of the otherwise easily displaced hook and eye fastening mechanism quite difficult. Also, the combination of the two interlocking mechanisms distributes the strain on the brassière and strap portions

and prevents an undue sagging at any particular point. If desired, the slip may be arranged so that it can be secured to the brassière before the latter is placed about the body of the wearer, particularly in cases where the wearer must secure the fastening devices. 5

When combined in the manner described, the slip covers at least a portion of the brassière and to an observer it would appear that the single shoulder straps are attached to the slip. The fastening devices are hidden from view, and the slip, which ordinarily is loosely fitted about the body of the wearer, is secured to the wearer more neatly than is possible with separate shoulder straps, due at least in part to the firm anchorage of the brassière to the body of the wearer. This arrangement provides for a neater dress than has been possible heretofore. 15

When constructed in accordance with my invention, the slips may be interchanged as desired and, in fact, the slips may be worn without a brassière by providing straps 22 having securing elements complementary to the corresponding elements on the slip, this structure being shown in Fig. 4. If desired, the straps for the brassière may be releasably secured thereto, but it is preferred to employ separate straps 22 where the slip is to be worn without a brassière. 20

An additional advantage of the structure described is that relative motion or movement between the brassière and slip is prevented. Therefore, the presence of the brassière is made more obscure and less suggestive, particularly in view of the single shoulder straps employed. It is practically impossible to prevent such under garments from being viewed about the neck of an outer dress when the former are constructed as customary heretofore, but the prominence of the under garments is reduced considerably by my improved structure. The exchange of garments is facilitated by my structure and considerable economy is effected by the elimination of separate straps for each slip. 30

Various changes in the particular structure described heretofore is possible without departing from the scope of the invention. For example, the arrangement of the fastening devices may be reversed, also, the particular construction of the individual garment. All such changes and modifications are intended to be included in the appended claim. 35

I claim:

In a garment construction, a brassière, a shoulder strap secured to said brassière, said strap having attached thereto one element of a snap fastening device and one element of a hook and eye fastening device, and a strapless under garment provided with the other element of said snap fastening device and the other element of said hook and eye fastening device. 40

PANSY H. JACKSON. 45
